SUPPORT STAND FOR A TOASTER AND A CANISTER SET

Joseph Stopryra, 1033 E. Hunting Park Ave.,
Philadelphia, Pa. 19124

Filed Aug. 8, 1967, Ser. No. 8,160

Term of patent 14 years

U.S. Cl. D33—3
Int. Cl. D6—01

Fig. 1.

Fig. 3.

Fig. 2.

Fig. 5.

Fig. 4.

Fig. 6.

FIG. 1 is a perspective view of a support stand for a toaster and a canister set, showing my new design;

FIG. 2 is a front elevation thereof;

FIG. 3 is a side elevational view taken from the right side of the device of FIG. 1 and with the left side elevation being identical;

FIG. 4 is a rear elevational thereof;

FIG. 5 is a top plan view thereof; and

FIG. 6 is a bottom plan view thereof with certain portions omitted for the sake of clarity.

I claim:

The ornamental design for a support stand for a toaster and a canister set, substantially as shown.
